UNITED STATES PATENT OFFICE.

DOMENICO P. FONTANA, OF NEW YORK, N. Y.

ATTACHMENT FOR LATHES.

Application filed April 6, 1922. Serial No. 550,070.

To all whom it may concern:

Be it known that I, DOMENICO P. FONTANA, a subject of the King of Italy, and a resident of the city of New York, borough 5 of Manhattan, in the county of New York and State of New York, have invented a new and Improved Attachment for Lathes, of which the following is a full, clear, and exact description.

10 This invention has relation to an improvement in lathes and refers more particularly to an attachment for metal lathes.

As an object the invention contemplates an attachment which constitutes a positive 15 means for preventing relative movement between the tool rest support and the work to preclude and prevent injury to the operator or spoiling of the work resulting from slippage of the tool rest support.

20 As a further object the invention contemplates an attachment of the character described which includes means for compensating for longitudinal and lateral adjustments of the tool rest support and locking 25 means adapted to coact therewith for positively retaining the elements in their adjusted positions.

More specifically the invention contemplates an attachment for lathes for the purpose 30 specified which constitutes a connection between the tool rest support and either the head or tail stock of the lathe whereby an auxiliary means for preventing relative movement between the tool rest support and the work is provided.

35 As a still further object the invention contemplates an attachment of the character described which is comparatively simple in its construction and operation, which is 40 thoroughly reliable and highly efficient in its purpose, and which may be readily installed and employed in connection with standard lathes now in general use.

With the above recited and other objects 45 in view, the invention resides in the novel construction set forth in the following specification, particularly pointed out in the appended claims and illustrated in the accompanying drawings, it being understood that 50 the right is reserved to embodiments other than those actually illustrated herein to the full extent indicated by the general meaning of the terms in which the claims are expressed.

In the drawings—

55 Figure 1 is a front elevation of a lathe with parts broken away to disclose the underlying structure, and illustrating the same equipped with an attachment constructed in accordance with the invention.

60 Fig. 2 is a plan view thereof.

65 Fig. 3 is a fragmentary detail view illustrating the attachment shifted for operation in connection with a tail stock.

Fig. 4 is an enlarged horizontal sectional view of the attachment taken approximately on the line 4—4 of Fig. 1.

70 Fig. 5 is a transverse vertical sectional view taken approximately on the line 5—5 of Fig. 4.

75 Fig. 6 is a detail fragmentary sectional view taken approximately on the line 6—6 of Fig. 5.

Referring to the drawings by characters of reference, A designates the bed plate of a 75 lathe upon which a head stock B and a tail stock C are supported. A tool rest support D including a base E and an upstanding tubular standard F which receives the shank G of the tool rest H is associated with the 80 bed plate of the lathe in the usual manner for longitudinal and lateral adjustments through the medium of the slotted portion I in the bed plate A and the clamp J which 85 extends through the slotted portion and co-acts with the base E.

85 By actual experience it has been found that the clamp J often permits of slippage and consequent relative movement between the tool rest support and the work, which 90 results in injury to the work or the operator. In order to overcome and positively prevent such occurrences, the attachment constituting the invention has been devised.

95 The attachment includes a forwardly or inwardly projecting stud or shaft section 10 rigidly secured in any desired manner or cast as a part of the tubular standard F upon which a member 11 is mounted, said member consisting of a substantially T-shaped sleeve, the head 12 of which receives the stud or shaft section 10 and the tubular stem 13 of which receives the reduced extremity 14 of a jack screw 15. The head and tail stocks B and C are longitudinally 100 tapped as at 16 and 17 to receive the jack screw 15. In order to provide a detachable 105 swiveled connection between the reduced

extremity 14 and the tubular stem 13, said reduced extremity is provided with an annular groove 18 with which the inner extremity of a retaining screw 19 is adapted 5 to cooperate when threaded into the tubular stem 13. The outer free end of the jack screw has formed thereon a manipulating handle 20 and lock nuts 21 are threaded to the jack screw for engagement with the 10 opposite ends of the tail stock after the proper adjustment of the screw through the tail stock has been obtained. The tubular head 12 of the member 11 is loosely mounted on the stud or shaft section 10 to permit of 15 the swinging of the member 11 to dispose the tubular stem 13 at either side of the stud or shaft section 10 and to compensate for lateral or transverse movement of the tool rest support D. In order to lock and retain 20 the tool rest support D in its lateral adjusted position with respect to the member 11, a retaining screw 22 having a manipulating handle 23 is threaded through the tubular head 12 and respectively cooperates 25 at its inner end with the upper and lower notches or depressions 24 and 25 in the stud or shaft section 10.

In use and operation of the device the jack screw 15 is threaded through the 30 tapped or threaded bores 16 or 17 of the head or tail stock according to the position and arrangement of the tool rest support with respect to the head or tail stocks. Where the tool rest support is disposed 35 closer to the head stock the jack screw is inserted and threaded through the tapped or threaded bore 16 of the head stop and the member 11 is swung to a position to dispose the tubular stem 13 at the left hand side of the stud or shaft section 10. The reduced extremity 14 of the jack screw is then received by the stem 13 and the retaining screw 19 is manipulated to engage with the 40 annular groove 18 in the reduced extremity 14 to swivelly couple the member 11 with the jack screw. The jack screw is then manipulated by means of the handle 20 to obtain the proper longitudinal adjustment of the tool rest support longitudinally of the leg. When the proper longitudinal adjustment has been obtained the lock or jam nuts 21 are threaded against the opposite 45 ends of the head stock and the lateral adjustment of the tool rest support is obtained. When the proper lateral adjustment has been accomplished, the retaining screw 22 is manipulated to bring its inner extremity into engagement with the desired notch or depression 25 on the under side of the stud or shaft section 10. In this manner the 50 tool rest support D is positively locked and retained against accidental displacement or relative movement with respect to the work. It is of course understood that the usual 55 clamping device J will be also manipulated,

thus doubly assuring the locking of the tool rest support in its adjusted positions. Where the tool rest support D is to be disposed closer to the tail stock C, the jack screw is removed from the head stock B and threaded into 70 the tapped or threaded opening 17 of the tail stock C. This is accomplished by unscrewing the retaining screw 19 to withdraw the same from the annular groove 18 of the extension 14, releasing the lock or 75 jam nuts 21, removing the inner jam nut 21, removing the jack screw and inserting the same into the tail stock. The retaining screw 22 is then retracted from the depressions or notches 25 on the under side of the 80 stud or shaft section 10 and the member 11 is swung to the reverse position to dispose the tubular stem 13 at the opposite side of the stud or shaft section 10. The retaining screw 22 is then manipulated to 85 cause its inner extremity to engage in one of the upper series of notches or depressions 24. The reduced extremity 14 is then inserted within the stem 13 and the retaining screw 19 is re-engaged with the annular 90 groove 18.

It will thus be seen that a comparatively simple and inexpensive attachment has been provided for use in connection with lathes to constitute a connection between the tool 95 rest support and the head or tail stocks which affords means for positively preventing accidental slippage or relative movement between the tool rest support and the work.

I claim:

1. An attachment for lathes comprising means detachably associated with the head or tail stock and longitudinally adjustable of the lathe, and means for detachably coupling the inner end of the first means with the tool rest support, said tool rest support being laterally adjustable with respect to the latter means.

2. An attachment for lathes comprising means detachably associated with the head or tail stock and longitudinally adjustable of the lathe, means for detachably coupling the inner end of the first means with the tool rest support, said tool rest support being laterally adjustable with respect to the latter means, and means for locking and retaining the tool rest support in its laterally adjusted positions.

3. The combination with a lathe including a head and tail stock and a tool rest support, of means adapted to be selectively associated with the head or tail stocks for longitudinal adjustments with respect to the lathe, and means for detachably coupling the first means to the tool rest support.

4. The combination with a lathe including head and tail stocks and a tool rest support, of an attachment therefor constituting means for positively locking the tool rest support in adjusted position to prevent rel-

ative movement between the same and the work comprising longitudinally threaded bores in the head and tail stocks, a jack screw adapted for respective association with said bores, a laterally projecting stud carried by the tool rest support, a coupling having detachable and swiveled association with the inner end of the jack screw and having laterally adjustable association with the stud, and means carried by said coupling for locking the stud in its laterally adjusted position.

DOMENICO P. FONTANA.
